CLAIM

The ornamental design for a rectangular lid for food container, as shown and described.

DESCRIPTION

FIG. 1 is a front view of a rectangular lid for food container showing my design;

FIG. 2 is a back view thereof;

FIG. 3 is a top view thereof;

FIG. 4 is a bottom view thereof;

FIG. 5 is a left view thereof;

FIG. 6 is a right view thereof; and,

FIG. 7 is a schematic view thereof.

(Continued)

The broken lines in the drawing depict environmental subject matter only and form no part of the claimed design.
